UNITED STATES PATENT OFFICE

154,566

DESIGN FOR A TILE FLOOR AND WALL COVERING BORDER STRIP

John E. Ryan, Danbury, Conn.

Application September 29, 1948, Serial No. 148,858

Term of patent 14 years

(Cl. D18—2)

To all whom it may concern:

Be it known that I, John E. Ryan, a citizen of the United States, residing at Danbury, in the county of Fairfield and State of Connecticut, have invented a new, original, and ornamental Design for a Tile Floor and Wall Covering Border Strip, of which the following is a specification, reference being had to the accompanying drawing, forming part thereof.

The figure is a plan view of a corner portion of a tile floor or wall covering border strip showing my new design, the design being subject to

such extension or repetition of the portion shown as may be necessary to cover any given border area.

I claim:

The ornamental design for a tile floor and wall covering border strip, as shown and described.

JOHN E. RYAN.
